his ATTORNEY.

UNITED STATES PATENT OFFICE.

OTIS A. HOLLIS, OF KNOXVILLE BOROUGH, PENNSYLVANIA.

PROCESS FOR ERECTING FORMS AND APPARATUS FOR CASTING CONCRETE WALLS.

Application filed June 18, 1926. Serial No. 116,814.

In constructing walls and other structures of concrete or similar material forms or matrices are employed to produce the desired thickness and also the desired surface characteristics of the structure, and such forms must be strong enough and rigid enough to produce the result in view, and must maintain their proper alinement until the material is fully set.

10 The most commonly used method of erecting a form is to build the same of lumber with its vertical sides anchored in place by braces. This method is expensive owing to the first cost of the material, and labor charges for erecting and tearing down after use; and the lumber is usually fit only for kindling when the form is torn down.

15 Forms or matrices which are assembled of elements adapted for repeated use have been designed, but the same have been expensive, and difficulty has been found in producing a sufficiently strong and rigid form in this manner, and in obtaining and maintaining proper alinement.

20 The object which I have in view is the provision of a new and improved process of erecting an inexpensive form or matrix for casting concrete walls and the like which will be sufficiently strong and rigid to properly contain and sustain the concrete and cause it to be molded accurately to the predetermined thickness and surface contour.

25 In my novel process I arrange a plurality of pairs of spaced apart matrix boards, each pair comprised of boards set on edge and parallel with each other, and the pairs being erected in superimposed or laterally abutting relation to each other to the desired height or length of the matrix. I position stay members against the outer sides and disposed transverse to and in overlapping relation with the matrix boards, overlapping a plurality of said boards to support the boards in position from without. I secure the stay members against outward movement by means of wire tie members which are disposed transversely of the matrix between the edges of adjacent pairs of matrix boards, the protruding ends of the tie members being looped and engaged by the stays. To hold the matrix boards of the pairs in proper spaced relation, I employ a wedging or stretching action by introducing temporary

struts between the matrix boards which force the boards outwardly against the stays, such struts being removed as the concrete is about to engulf the same.

30 The matrix produced by my process is of novel and advantageous character.

I have also invented new and improved forms of wire tie members.

Other novel features of construction and also of arrangement of parts will appear from the following description.

35 In the accompanying drawings which are intended to illustrate the working of my new process, Fig. 1 is a perspective showing a form of matrix, characterized by horizontally disposed matrix boards, for casting a concrete wall; Fig. 2 is an end view of the same; Fig. 3 is a view similar to Fig. 1 but showing a slightly different arrangement of the tie member and stays; Fig. 4 is a similar view showing the matrix boards arranged vertically and the stays horizontally; Fig. 5 is an enlarged view in plan of the preferred form of my improved wire tie; Fig. 6 is a similar view of the double-loop form of tie; Fig. 7 is a view similar to Fig. 5 but showing a modification, and Fig. 8 is an enlarged detail of the tie shown in Fig. 7.

40 Referring first to Figs. 1, 2, 5 and 6 of the drawings, according to my process of erecting the form or matrix I arrange a plurality of pairs of matrix boards, in this case horizontally disposed, and indicated generally by the reference numeral 1, substantially as shown in Figs. 1 and 2, wherein I illustrate five pairs of matrix boards shown at 1^a—1^a; 1^b—1^b; 1^c—1^c; 1^d—1^d; and 1^e—1^e set on edge and the members of each pair being spaced apart when the matrix is assembled to the degree required to provide for the desired thickness of concrete.

45 To hold the matrix boards of the pairs against separation I provide the stays 2 disposed transversely to the matrix boards, which I arrange to bear from without against the matrix boards as shown in the drawings, the stays overlapping a plurality of the matrix boards.

50 The stays are held in position by their extension through the looped ends of the wire ties 3 which are transversely disposed between the edges of adjacent pairs of matrix boards as shown.

Thus the degree of separation between the boards of the pairs is determined by the length of the ties. The ties are pre-formed in standard lengths to provide for casting different thicknesses of concrete.

The ties may be single loop members as shown at 3 in Fig. 5 and as shown at the left in Fig. 1, or they may be multiple loop members as illustrated at 3^a in Fig. 6.

As the height or extent of the matrix is increased additional stays may be introduced and the same may be held in place by tie members 3, the upper ends of the lower stay members or one set of said members overlapping the lower ends of the other or upper stay members. Or where multiple loop ties, such as shown at 3^a are employed, the overlapping stay members have their overlapping ends engaging the different loops of the tie member. In making the wire stays the ends of the wire may be welded, as indicated at 3^b or otherwise attached together.

In Fig. 3 I show the stays doubled either set flat against the matrix boards or on edge. By this means, where the stays are lath, additional strength may be obtained.

In Fig. 4 I show the matrix boards 1 vertically disposed while the stay members are horizontally disposed. Thus the matrix for a wall may be extended in a horizontal direction to the desired length of wall to be constructed.

I wedge the matrix boards outwardly against the stay members by means of internal struts 4 which may conveniently be short lengths of wooden planks or scantling and which are driven snugly in place, thus placing the matrix boards in compression against the stays and the ties in tension also against the stays. Thus the looped ends of the ties grip the stays and clamp them against the exterior surface of the matrix boards, while the matrix boards are simultaneously wedged outwardly against the stays by the struts. The struts are removed as the matrix becomes filled with concrete.

Any suitable material may be employed for the stays, but I prefer to use wooden members or strips, and for this purpose I have found ordinary wooden lath to be entirely satisfactory. However, more substantial wooden members such as "two-by-fours" may be employed.

The lath or other equivalent members of relatively yielding material have a very practical and important advantage over metal rods or bars as stays, inasmuch as the tension imposed on the ties by the wedging action of the struts causes the ties to bite slightly into the wooden stays, thus obtaining a very firm grip on the stays which in turn are thereby pressed tightly against the sides of the matrix boards.

The frictional contact between the wooden stays and the plurality of matrix boards

they overlap, ties the abutting courses of matrix boards firmly together and thus stiffens the matrix against endwise or racking movement. Thus the matrix as a whole is much stiffer and more rigid than one in which metal rods are employed as stays, and such a matrix will more perfectly maintain its alignment.

The lath or other wooden stays are also positively held by the bite of the wire ties against accidental displacement or danger of vertical slipping.

Wooden boards of relatively thin material and of inexpensive quality may be used as matrix boards. It is evident that the matrix may be erected to the desired height or extent and the concrete poured to cast therein, or the matrix may be built up step by step as the concrete structure rises, the matrix boards being removed from the lower courses after the concrete has hardened and reerected above.

The looped ends of the wire ties which protrude from the surface of the concrete after the matrix boards are removed are clipped off snug up against the surface of the concrete and the bodies of the ties remain permanently embedded in the concrete.

Where lath or light wooden members are employed as stays the looped ends of the wire ties tend to bite deeply into the wood to a greater degree than is necessary to firmly hold the matrix assembled and bite, occasionally, to an extent sufficient to impair the strength of the stays in supporting the matrix boards from without.

Thus I find it advantageous to provide the looped ends of the wire ties 3 and 3^a with means for broadening or extending their bearing surfaces on the stays, thus reducing the tendency of the wire to bite too deeply into the stays, but in no wise impairing the efficiency of the grip which the ties have on the stays.

Thus in Figs. 7 and 8 I show the wire coiled in helical form at the looped ends. A convenient method of obtaining this result is to form the tie of two lengths of wire 3^b—3^c with their ends bent inwardly and twisted at the center, as shown at 5 and the extremities coiled about each other to form the twin helices 6.

The economy attending the use of my process will be evident to those skilled in the art. Owing to the manner of supporting the matrix boards in place they may be relatively thin wooden boards of inexpensive quality and they may be used repeatedly, as they are not injured in assembling or disassembling the matrix. The struts which are removed as the concrete is filled up thereto in the matrix may also be used repeatedly and they may be short lengths of plank or board usually considered as waste. The wire ties are inexpensive to make and are manufac-

tured in a number of different sizes for different thicknesses of wall structures. The lath of course are very inexpensive.

With these elements the matrix may be assembled by unskilled labor, as the width of the matrix is determined by the length of the ties and the matrix boards are automatically brought into and held in proper position and alinement by the introduction 10 of the struts.

Where lumber forms are built as in the present more common practice, skilled carpenters must be employed and a high quality of lumber used as the form must be carefully 15 constructed in proper alinement and must be strong and rigid enough to sustain the burden of the concrete without giving. Thus lumber such as planks, scantling and beams must be cut, fitted and nailed together. 20 When the form is to be removed it is torn to pieces and it is rarely true that much of the material is fit for reuse in form building.

In taking down the matrix after the concrete has set, the wire ties are cut adjacent 25 to the matrix boards, thus releasing the stays, and after the stays have been removed, the matrix boards may be stripped off, and the protruding ends of the wires 30 clipped off close up against the surfaces of the concrete.

When relatively light stays, such as wooden lath are employed I prefer to double them to give additional strength and to insure proper alinement of the matrix 35 boards, by having the ends of the laths break joints, as shown in Fig. 4. I obtain a very reliable stay member which may be extended indefinitely without loss of strength or alinement.

40 What I desire to claim is:—

1. For use for the purpose described a wire tie member having its ends pre-formed

into loops to receive the stays, the portions of the loops bearing on the stays being provided with broadened bearing surfaces to 45 prevent excess biting into the stays.

2. For use for the purpose described a wire tie member having its ends pre-formed into loops to receive the stays, the loops being wrapped with metal to prevent excess 50 biting into the stays.

3. For use for the purpose described a wire tie member having its ends preformed into loops to receive the stays, the loops being wrapped with wire to prevent excess 55 biting into the stays.

4. A process for erecting a form or matrix for receiving concrete or the like which consists in arranging a plurality of pairs of opposing parallel matrix boards, the pairs 60 being positioned one after the other, positioning transverse supporting stays against the outer sides of said boards with transversely disposed wire tie members lying between the opposing edges of the pairs of 65 matrix boards and having looped end portions engaging said stays, said tie members being preformed to provide a predetermined effective length, said stays overlapping a plurality of said matrix boards, and thereafter interposing struts between the members of the pairs of matrix boards for the purpose of producing a wedging and spreading effect to force said matrix boards outwardly and to cause the looped ends of the ties to 70 tightly grasp the stays and clamp the latter against the outer faces of the matrix boards, the effective length of the tie members determining the effective width of the form or 75 matrix.

Signed at Pittsburgh, Pa., this 7 day of June, 1926.
